UNITED STATES PATENT OFFICE.

GEORGE A. HENSLEY, OF MONTA VISTA, CALIFORNIA.

AMUSEMENT APPARATUS.

Application filed February 12, 1923. Serial No. 618,453.

To all whom it may concern:

Be it known that I, GEORGE A. HENSLEY, a citizen of the United States of America, and a resident of Monta Vista, county of 5 Santa Clara, and State of California, have invented a certain new and useful Amusement Apparatus, of which the following is a specification.

The invention relates to an amusement apparatus comprising a dance floor which is 10 delineated to introduce features of novelty into dancing. An object of the invention is to provide a dance floor which introduces greater pleasure into dancing. Another object of the invention is to provide a dance 15 floor which incorporates the chance of receiving a bonus or present with the pleasure of dancing.

The invention possesses other advantageous features, some of which, with the foregoing, will be set forth at length in the following description, where I shall outline in full that form of the embodiment of my invention which I have selected for illustration in the drawings accompanying and forming part of the present specification. In said drawings, I have shown one form of apparatus embodying my invention, but it is to be understood that I do not limit myself to such form, since the invention, as set forth in the claims may be embodied in a plurality of forms.

Referring to said drawings: Figure 1 is a perspective view, somewhat diagrammatic, 35 of a ball-room arranged in accordance with my invention. Fig. 2 is a plan view of a dance floor embodying my invention. Fig. 3 is an elevation of the uncontrollable selecting device forming part of my invention.

In accordance with my invention I provide 40 means for adding to the pleasure of dancing by introducing the elements of chance. The dance floor is divided into a plurality of areas of different colors and having different numerical values, and at the end of a dance, 45 presents or bonuses are awarded to the dancers standing on the areas corresponding in color and number value to the color and number selected by any uncontrollable apparatus, such as a wheel of chance, which is 50 divided into sections of different color, each of which sections has a numerical value. Thus, if the wheel of chance stops at a blue section bearing the number 3 the persons

standing on the blue sections of the floor 55 will receive bonuses or presents of one nature and the couple standing on the area having the numerical value of 3 will receive a present or bonus of a different nature.

In accordance with my invention the dance 60 floor is preferably divided into a plurality of contiguous areas, preferably rectangular in shape. These areas may be defined by lines formed in or on the floor or may be defined entirely by the colors of the various 65 areas. In accordance with my invention a plurality of the areas are colored with one color, for instance blue, a plurality are colored with another color, for instance red, and other areas are colored with another 70 color, for instance black. These areas are distributed over the floor so that they occur in different parts thereof and so that all of the areas of one color are not congregated. The floor is further provided with 75 a plurality of uncolored or neutral areas, in so far as color is concerned, which color neutral areas have different numerical values and these numerical value areas are distributed over the dance floor. The numerical 80 values of the areas may be indicated by painting on the floor or by inserting metal numerals in the floor, or by arranging illuminated numerals in the floor or by other means. There is thus provided a dance floor 85 having a plurality of areas of numeral value and a plurality of series of areas of color value, the areas of each series being of the same color.

Means are also provided, which are visible 90 from all parts of the dance floor for uncontrollably selecting a number and a color. This means may consist of the image of a wheel of chance or roulette wheel which is projected by a stereopticon or other 95 means onto one of the walls of the ballroom. The transparent slide in the stereopticon has a rotatable portion carrying a circular band of numbers corresponding to the numbers on the dance floor arranged on colored areas, 100 the colors corresponding to the colors of the areas on the dance floor. The rotatable portion of the slide in the stereopticon 3 is rotated causing a rotation of the image 4 on the wall and when the rotatable portion of the slide comes to rest an indicator 5 on the wall points to the numeral and color selected.

As the dance approaches its end a signal is given and the wheel is spun. The various dancers then choose their positions on any of the areas of the floor and when the wheel comes to rest those persons standing on the colored areas which correspond to the color indicated by the indicator 5 receive bonuses or presents of one nature. The couple standing on the area having the numerical value of 10 the number selected by the indicator 5 receive a present or bonus of a different nature.

On the floor shown in the accompanying drawing there are seven red areas A, seven blue areas B and seven black areas C. 15 There are twenty-one numeral areas D, the number of areas into which the floor is divided may be varied to suit the size of the floor, and it is to be understood that this invention is not limited to the specific arrangement of the floor shown in the drawing. Since there are seven more chances of the selected color number being selected by the indicator than there are for the selected numeral value to be selected by the 20 indicator the couple standing on the numeral value will receive a present or bonus approximately seven times the value of the present or bonus received by the couples standing on the color value.

30 This arrangement may be advantageously used in connection with what are known as "pay as you enter" dances, in which the couple pay a fee every time they enter upon the floor, and the value of the bonuses distributed at the end of each dance will be approximately equal to the amount received in fees for the dance less the cost of operation of the dance.

Dance floors have been proposed heretofore having numbered spots and at the end of the dance a number was selected by a wheel of chance and the couple standing on that number received a present. The limitations of that system however were that 40 only one couple could receive a present in any one dance, whereas, in the present system a large number of couples may receive presents at the end of every dance. This introduces the much sought after

"sporting chance" into the dance and 50 renders it much more enjoyable.

The "lucky number" and color may be selected in any desired manner and it is to be understood that it is not necessary that a projection machine be employed, but such 55 arrangement is desirable since it permits all of the dancers to immediately perceive the selected number and color.

I claim:

1. The combination with a dance floor 60 having alternate areas of different color and number value, of means for selecting by chance one of said colors and one of said numbers.

2. The combination with a dance floor 65 having a plurality of areas of one color and a plurality of areas of another color, and a plurality of areas of different numerical value, of means for selecting by chance, one of said colors and one of said numbers. 70

3. A dance floor having a plurality of areas of one color, a plurality of areas of another color and a plurality of areas of different numerical value, said areas being arranged in a plurality of rows in which the 75 numerical and colored areas are alternately arranged.

4. A dance floor having a plurality of series of areas, the areas of one series being of a different color from the areas of the 80 other series, a plurality of areas having numerical value, a wall adjacent said floor and means for projecting on the wall the image of one of said numbers and one of said colors. 85

5. The combination with a dance floor having a plurality of distributed areas of one color, a plurality of distributed areas of another color, a plurality of distributed areas having different numerical value, said 90 areas being arranged in a plurality of rows in which the numerical and colored areas are arranged alternately and means visible from all parts of the floor for selecting one of said colors and one of said numbers. 95

In testimony whereof, I have hereunto set my hand.

GEORGE A. HENSLEY.
